BRACELET

Julius A. Welebny, Oceanside, N. Y.

Application January 30, 1956, Serial No. 39,963

Term of patent 7 years

(Cl. D45—4)

Fig. 1 is a front elevational view of a bracelet showing my new design, the portion shown in solid lines being continued throughout the circumference as indicated by the broken lines;

Fig. 2 is a side elevational view thereof;

Fig. 3 is a sectional view taken along the line 3—3 of Fig. 1 in the direction of the arrows; and

Fig. 4 is a sectional view taken along the line 4—4 of Fig. 2 in the direction of the arrows.

I claim:

The ornamental design for a bracelet, substantially as shown and described.
